UNITED STATES PATENT OFFICE.

ARSENE SAULNIER, OF WALTHAM, MASSACHUSETTS.

CLOCK FOR WARPING MACHINES.

Application filed January 22, 1921. Serial No. 439,128.

To all whom it may concern:

Be it known that I, ARSENE SAULNIER, a citizen of the United States, residing at Waltham, in the county of Middlesex, State 5 of Massachusetts, have invented a certain new and useful Improvement in Clocks for Warping Machines, of which the following is a specification, reference being had therein to the accompanying drawings.

10 The invention has relation to the so-called clocks which are employed in warping and other machines for the purpose of registering the length of assembled threads which passes through a machine, and of bringing about the stopping of the machine when a predetermined measured length has passed. It further has relation to clocks on the order of what are termed 15 lease-clocks, these being contrived to cause 20 stoppage of the machine at intermediate points during the passage of the total predetermined length of assembled threads, for the purpose of enabling lease-threads or 25 cords to be introduced at predetermined intervals among the assembled threads.

In usual practice, the clock of a warping machine comprises a spirally grooved barrel, called a scroll, and a follower engaging in the spiral groove of the scroll. The scroll is geared with a measuring roll which is rotated through the contact of the traveling yarns with its periphery, and the follower is traversed by the thread of the scroll as the latter rotates, and arranged to 30 act in connection with other parts with which it is associated to indicate into action at the required time or times the stop motion mechanism of the machine. In the case of some warping machines the clock brings 35 about the stoppage of the machine only on the completion of the required total length of assembled threads. In the operation of a lease-warper the clock causes arrest of the machine after a certain number of yards 40 has passed through, whereupon the attendant introduces lease-threads or cords and restarts the machine, the stoppage, introduction of lease-threads or cords, and restarting being repeated at intervals until the final 45 automatic stoppage of the machine which indicates the passage of the total predetermined length.

Trouble and loss are experienced often in practice in consequence of accidental dis-

placement of the follower of a clock relative to the turns of the spiral of the clock scroll. Such displacement results in false registration by the clock, and in inaccurate measurement, involving for instance either too many or an insufficient number of 55 yards of threads being passed through the machine. Displacement is not detected readily, and usually passed unobserved so that the error is not discovered until later on in the handling or use of the assembled 60 threads.

What has just been stated will be more clearly apparent after reference to the practice in connection with beam warpers. A beam warper is employed to wind threads 70 on a beam, from spools mounted in a creel, until the required length of threads has been thus wound. The number of threads thereby wound upon the beam is a fractional part of the entire number of threads required to make the contemplated warp, and constitutes one so-called section of the warp. In like manner as many sections are wound upon other beams as are necessary to make up the required total of the threads for the 75 said warp. All of the sections are combined at the slasher, and after passing all together through the latter are wound upon a single beam in readiness to be placed in a loom. Obviously all the sections of a 80 warp should be of the same length. If one or more sections, through error in the winding thereof upon the corresponding section beam or beams, should be either shorter or longer than the others, loss or trouble would 85 result. The excess of length in the case of the longer section or sections of a warp would become waste.

The object of my invention is to prevent displacement of the follower, and to this 90 end my invention comprises, firstly, means for locking the follower normally from being disengaged from the spiral of the scroll; and secondly, means for keeping the follower in working relations with the 95 proper turn of the scroll-spiral by preventing entry of the follower into the wrong turn in passing from a lease-groove, the latter means preferably being so contrived as to prevent the follower from engaging with 100 the wrong turn even after being lifted from the normal position.

Illustrative embodiments of the two por-

tions of the present invention are shown in the accompanying drawings, in which,—

Fig. 1 is an elevation of a portion of one side-frame of a warping machine and a lease-clock containing the said embodiment.

Fig. 2 is a view of the same in vertical section on line 2, 2, of Fig. 1, looking toward the right in Fig. 1.

Fig. 3 is a view in horizontal section on line 3, 3, of Figs. 1, 2 and 4, looking downward, and with gear-wheels omitted.

Fig. 4 is a view in elevation on a somewhat larger scale than the preceding views, showing the parts which more immediately 15 are involved in the invention.

Fig. 5 is a detail view looking from the left hand side in Fig. 4.

Having reference to the drawings:

One side-frame 1 of a warping machine is shown in Figs. 1, 2 and 3. The measuring and registering devices shown in the drawings include the measuring roll 2 which, as usual, is rotated through the contact of the traveling yarns with its periphery, the spirally grooved scroll 10, and motion-transmitting connections by which the rotation of measuring roll 2 serves to cause the scroll to rotate. The said connections, (see Fig. 1) comprise in this instance the worm 4 on one journal 3, of the measuring roll, the worm-wheel 5 engaged by the said worm, and the train of gearing connecting the worm-wheel 5 with the scroll 10, comprising a small gear 6 attached to said worm-wheel 5, a carrier gear 7 meshing with gear 6, the so-called cut-gear 8 meshing with gear 7 and having attached to it a small gear 9 meshing with the change gear 11 having connected therewith the small gear 12 meshing with the so-called lease-gear 13 fast on the shaft 13* of the scroll 10. The various gears and the scroll-shaft 13* are suitably mounted in connection with the upright portion 13* of the clock-frame. The follower-arm 14 is provided with a projection 15, Figs. 1 and 3, working in the spiral groove of the scroll 10 and adapted to drop into the longitudinal lease-groove 10*, and into the final stopping-notch 10*. The said follower-arm, as heretofore, is hung upon the rockshaft 17 of the indicating devices, and as usual is adapted to slide along the said rockshaft in being traversed by the action of the scroll as the latter turns. As heretofore in some cases, a presser-finger 17* fixed upon the rockshaft 17 beats upon a laterally extended portion 14* of the follower-arm 14 under the turning effect imparted by the weight-arm 17* at one end of the rockshaft. Through this engagement of presser-finger 17* with the follower-arm the latter and the rockshaft are caused to turn in unison about the axis of the rockshaft. The projection 15 of the follower is kept down against the bottom of

the spiral groove of the scroll by the weight 65 of the follower and of the said weight-arm. The groove-bottom sustains the follower so as to keep the rockshaft 17 rocked into a position in which the tripping-finger 17* in connection with weight-arm 17* is clear of the coacting stop-motion devices (not shown), so as not to interfere with the running of the machine. Each time during the rotation of the scroll the lease-groove 10* (which is deeper than the scroll-groove) is presented 75 in position to receive the projection 15 the follower drops, so as to cause rockshaft 17 to be rocked and the trip-arm 17* to be moved so as bring about unshipping of the driving power and the stopping of the machine for 80 the insertion of the lease-cords or threads. So, also, when the follower has been traversed out to the outer end of the scroll and the final stopping-notch 10* is presented in position to receive the projection 15 of the 85 follower, the follower drops and the rockshaft and trip-finger are rocked to bring about the stoppage at the conclusion of the required total number of yards of threads passed through the machine.

In the case of warper clocks not equipped with my invention it happens often that the follower is disengaged from the scroll-groove or thread, either accidentally or thoughtlessly, and either is not at once restored to 90 engagement, or in being reengaged does not become engaged in or with the same turn from which it was withdrawn. Accidental disengagement may occur as a result of an attendant in working around a warper, as 95 when occupied with the cleaning thereof, hitting or pushing against the follower. Other disengagements result sometimes through absent-minded or thoughtless lifting of the follower, and sometimes are due 100 to casual meddling by persons passing by or observing the operation of the mechanism. If, while the machine is in operation, with yarns passing therethrough, the follower is disengaged from the scroll and not instantly 105 restored to engagement with the same turn of groove or thread, at the identical point of such turn from which it was taken, the registering function of the clock will be interfered with and the final stoppage will not 110 correspond with the passage of the correct number of yards of threads. Even though the follower is restored with comparative promptness to engagement with the same turn, the total length that will have passed 115 through the machine up to the time of final stoppage through the entrance of the follower into the notch 10* will exceed the correct length by the number of yards that pass between the instant of withdrawal of the follower and the instant of its reengagement. An excess of inconvenient amount occurs in 120 cases in which the follower, after being dis-

engaged, lands upon the rib between the turn last occupied by it and one of the adjoining turns, and remains supported upon such rib for a while before dropping back into the former turn. The exact length that has passed through the machine is not obvious upon inspection of the wound mass of threads, and can only be approximated by weighing such mass. Consequently, errors in length frequently pass unobserved for the time being; when suspected or known, the extent thereof is not easy of ascertainment and usually accuracy in the correction thereof is difficult of accomplishment. If the follower, after having been lifted, drops into an adjoining turn either preceding or following the turn from which it was lifted, and either directly in being returned toward working relations or after first having landed upon the intermediate rib, the total length passed through the machine up to the final stoppage may be greatly in excess or greatly below the required length. Just how much, can be ascertained only by weighing what has passed through; the extent of the error cannot be determined merely from looking at the scroll and follower.

Referring now to the first portion of the invention, namely, the follower-lock for holding the follower from being disengaged from the spiral of the scroll: The precise constructional form of follower-lock adopted in practice, and the precise place and manner of application of the same, may vary more or less, and will be governed by the construction and specific mode of operation, etc., of the warper-clock, or of the warper itself, and by the views and requirements of builders and users of the mechanism. The illustrative embodiment of this portion of the invention which is represented in the drawings comprises a form of follower-lock which is adapted more especially for use in connection with a warper-clock in which, as ordinarily in practice, and as more or less fully set forth in the preceding description, relative traverse between the scroll and the follower is provided for by arranging the follower to traverse lengthwise of the scroll, and in which the follower is movable lengthwise of the axis of the rockshaft 17 of the indicating rocker and combined with the said rockshaft in a manner which causes them to turn in unison around the said axis.

The illustrated follower-lock is arranged to lock the indicating rocker from being rocked in the manner that is required in order to permit the follower to be disengaged from the scroll-groove; more specifically, it is arranged for direct cooperation with the rock shaft 17 of the said rocker. It comprises a movable dog *a* adapted for coaction with a tooth or shoulder *b* in connection with the said rockshaft. Such tooth

or shoulder in this instance is provided upon a collar *c* that is mounted upon the rockshaft and held fast thereon by means of a screw *d*. A spring *e* acts on the locking dog with a tendency to move it into engaging position, 70 and a wire or rod *f* extends upward from the dog to a point where it conveniently may be reached by the hand of the attendant. The tooth or shoulder *b* is so related to the rocker, and the dog *a* to the said tooth or shoulder, 75 that when the follower projection is in the scroll-spiral the tooth or shoulder *b* is presented in such position to the dog that it is adapted to be and is engaged by the dog, and by such engagement the follower is 80 locked from removal from the scroll-groove because the rocker cannot be turned far enough to allow the follower to be lifted sufficiently to withdraw the projection 15 from the scroll-groove. At the same time, 85 the relations and mode of engagement of the dog and tooth or shoulder afford freedom to the follower to drop slightly when the cross-groove 10^a, otherwise termed lease-groove, is presented to the follower projection 15 in 90 the rotation of the scroll, and also when the final stopping notch 10^b is presented in position to receive the said projection. The wire or rod *f* provides for manual control of the lock by enabling the dog to be lifted 95 clear of the tooth or shoulder whenever required. When the dog is lifted, as by means of the said wire or rod, the follower is unlocked and may be swung out of engagement with the scroll.

The tooth or shoulder *b* is slightly undercut, as shown in Fig. 5, and overhangs the engaging end of the dog *a* to an extent sufficient to guard against the dog being shaken or otherwise accidentally dislodged from the 105 tooth or shoulder while the follower occupies the slightly dropped position assumed by it when projection 15 enters the cross or lease-groove 10^a of the scroll.

Referring now to the second portion of 110 the invention, namely the means for keeping the follower in correct working relations with the proper turn of the scroll-spiral even though lifted from its normal position, and for preventing entry of the follower 115 into the wrong turn of the scroll-spiral in passing from a lease-groove in the scroll:—

For the attainment of the purposes just mentioned I provide in connection with the follower what I call an aliner. In the case 120 of this device, as also in that of the follower lock, the precise constructional form thereof, and the precise mode of combining the same with the follower may be varied more or less in practice. In the illustrative embodiment of this portion of the invention that is shown in the drawings the aliner, therein marked *h*, is of the general form of a blade, and is movably combined with the follower by being pivoted at *i*, at one end 125

thereof, to the upper portion of the tottower-arm so that the aliner swings down toward the periphery of the scroll and its under edge enters the scroll-groove. The outer 5 end of the aliner is extended to form a convenient handle by means of which the aliner may be moved by hand when required, and also for the advantage of the increased weight, the weight of the aliner aiding to 10 keep the said edge in the groove. In this instance the aliner trails in the scroll-groove, in the same turn of the latter that is occupied by the follower-projection 15. By reason of the movable connection of the 15 aliner with the follower, the aliner remains in the scroll-groove even though the follower be lifted sufficiently to withdraw the projection 15 from the groove. Consequently, the return of the said projection to the particular 20 turn of the scroll-groove from which it was removed is ensured.

In the operation of a lease-warper, and following the automatic stopping of the machine which results from the dropping of 25 the follower-projection 15 into a lease-groove, and also after the lease-threads or cords have been inserted among the threads, it is customary to insert a stick into the lease-groove under the projection 15, and 30 permit it to remain there temporarily following the restarting of the machine. This stick serves to support the said projection high enough in the lease-groove to enable the projection to pass from the lease-groove 35 into the continuation of that turn of the spiral groove in which it was contained prior to dropping into the lease-groove. Comparatively often, as a result of carelessness or lack of skill, the stick in being inserted 40 hits against the projection 15 and thereby, in the case of warper-clocks unprovided with the second portion of my invention, moves the follower sidewise, that is to say in the direction of the length of the scroll- 45 axis, thereby shifting the projection along the lease-groove into a position causing it to enter a wrong turn of the spiral groove. This, if unobserved, makes a difference of one or more (as the case may be) turns of 50 the spiral, representing a difference of a large number of yards of threads. The aliner, by occupying a position in the spiral groove while the follower-projection is in the longitudinal cross or lease-groove, prevents 55 lateral displacement of the follower at such time, either through being hit or pushed by the stick, or otherwise accidentally disturbed by the attendant or some other person about the machine, or as a result of jarring of the mechanism.

The aliner may either follow (as in the present instance) the follower-projection in the spiral groove, or precede it. It preferably is movably combined with the follower 60 in order that it may gravitate or be pressed

as by a spring into the spiral groove, and in order that normally it may remain therein when the follower is raised. However, it may be fixedly combined with the follower. The extent to which the aliner is 70 separated from the follower-projection 15 may vary more or less; in case the aliner is a fixed part, it may be an extension from the said projection.

What is claimed as the invention is,— 75

1. The combination, in a registering clock mechanism, with a measuring roll, a spirally-grooved scroll that is rotated through the rotation of said roll, an indicator-follower engaging in the spiral groove of said scroll and traversed by the scroll for registering purposes, and a rocker, axially of which the said follower moves in the registering action and with which the follower is connected so that the follower and rocker turn in unison, of locking means by which the rocker is held from turning and the follower prevented from being lifted out of engagement in the scroll-groove. 80

2. The combination, in a registering clock 90 mechanism, with a measuring roll, a spirally-grooved scroll that is rotated through the rotation of said roll, an indicator-follower engaging in the spiral groove of said scroll and traversed by the scroll for registering purposes; and a rocker axially of which the follower moves in the registering action and with which the follower is connected so that the follower and rocker turn in unison, of manually-controlled locking 95 means locking the rocker from turning and preventing the follower from being lifted out of engagement in the scroll-groove. 100

3. The combination, in a registering clock mechanism, with a rotating spirally-grooved 105 scroll and an indicator-follower engaging in the groove thereof, rotation of the scroll producing relative traversing movement of one of said parts lengthwise of the scroll-axis for registering purposes, of a follower-lock by which the follower is locked from removal from the scroll-groove. 110

4. The combination, in a registering clock mechanism, with a rotating spirally-grooved scroll, and an indicator member engaging in the groove thereof, rotation of the scroll producing relative traversing movement of one of said parts lengthwise of the scroll-axis for registering purposes, of a lock by 115 which the said member is locked from withdrawal from the scroll-groove, without interfering with the traverse and also without interfering with radial inward indicating movement of such member. 120

5. A measuring clock having a scroll and a follower engaging with the thread of the scroll and traversed thereby, and means for locking the said follower in engagement with the said thread during the traverse. 125

6. The combination with a scroll, a fol- 130

- lower, and a rock-shaft turning in unison with said follower, of a locking tooth or shoulder in connection with said rockshaft, and a manually-controlled locking dog engaging with said tooth and thereby locking the follower so as to prevent it from being withdrawn from engagement with the scroll-spiral.
7. The combination with a scroll having 10 depressions into which the follower enters for stopping purposes, a follower, and a rockshaft turning in unison with said follower, of an undercut locking tooth or shoulder in connection with said rockshaft, 15 and a manually-controlled locking dog engaging with said tooth and thereby locking the follower so as to prevent it from being withdrawn from engagement with the scroll-spiral.
- 20 8. In a measuring clock, the combination with a rotating spirally-grooved scroll having a cross-groove, and an indicating follower engaging in the scroll-groove, cooperating with the scroll to produce relative 25 traversing movement, and entering the said cross-groove for indicating purposes, of a secondary follower-device also engaging in the scroll-groove and operating to prevent entry of the scroll-engaging part of the follower into the wrong turn of the spiral 30 groove in passing from the cross-groove.
9. In a measuring clock, the combination with a rotating spirally-grooved scroll having a cross-groove, and an indicating follower 35 engaging in the said scroll-groove, cooperating with the scroll to occasion relative traversing movement, and entering the said cross-groove for indicating purposes, of an aliner also engaging with the scroll 40 and operating to keep the scroll-engaging part of the follower alined with the proper turn of the spiral groove while occupying and passing from the cross-groove.
10. In a measuring clock, the combination 45 with a rotating spirally-grooved scroll having a cross-groove, and an indicating follower engaging in the scroll-groove, cooperating with the scroll to produce relative traversing movement, entering the cross-groove for indicating purposes, and movable 50 radially of the scroll into and out of engagement in the scroll-groove, of an aliner also engaging in the scroll-groove and operating to keep the scroll-engaging part of the follower alined with the proper turn of the spiral groove while occupying the cross-groove and in passing therefrom, and movably 55 combined with the follower so that it remains engaged in the scroll-groove when the follower itself is disengaged from said groove, thereby ensuring that in restoring the follower to engagement it shall be replaced in the turn from which it was withdrawn.
11. In a measuring clock, the combination 65 with a rotating spirally-grooved scroll having a cross-groove, and an indicating follower engaging in the scroll-groove, cooperating with the scroll to produce relative traversing movement, entering the cross-groove for indicating purposes, and movable 70 radially of the scroll into and out of engagement in the scroll-groove, of an aliner pivotally connected with the follower, normally occupying the scroll-groove and operating to keep the scroll-engaging part of the follower alined with the proper turn of the spiral groove while within and in passing from the cross-groove, and remaining engaged in the scroll-groove when the 75 follower itself is disengaged therefrom so as to ensure return of the follower into the said turn in being restored to engagement.
12. In a measuring clock, the combination 80 with a rotating spirally-grooved scroll, and an indicating follower engaging in the scroll-groove, cooperating with the scroll to produce relative traversing movement, and movable 85 radially of the scroll into and out of engagement in the scroll-groove, of an aliner movably connected with the follower, normally occupying the scroll-groove, remaining therein when the follower is lifted out of such groove, and ensuring return of the follower to the proper turn of the 90 groove in being restored to engagement.
13. In a measuring clock, the combination 95 with a rotating scroll, an indicating rock-shaft adjoining said scroll, a follower-arm hung upon said rockshaft, engaged with the spiral of said scroll, and traversed by the scroll for registering purposes, and means connecting the said follower-arm and the rockshaft to turn in unison, of a manually-controlled lock for preventing the arm and 100 rockshaft from being rocked to disengage the arm from the said spiral, and an aliner movably combined with the follower-arm and remaining engaged with the scroll-spiral when, following unlocking, the follower-arm is lifted from the scroll-spiral.
14. A lease-clock comprising a scroll having a transverse lease-groove, an indicating follower engaging with the spiral of the scroll and traversed thereby, locking means 115 for holding the follower down in engagement with the scroll-spiral, and an aliner pivotally connected with the follower and also engaged with the scroll-spiral for preventing entry of the follower into the wrong 120 turn in passing from the lease-groove.

In testimony whereof I affix my signature in presence of two witnesses.

ARSENE SAULNIER.
